Primary Examiner — Sandra Snapp*Assistant Examiner* — Altaira J Swangin(57) **CLAIM**

The ornamental design for a portable dual-screen monitor, as shown and described.

DESCRIPTION

FIG. 1 is a perspective view of a portable dual-screen monitor showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is an enlarged view of FIG. 6;

FIG. 9 is an enlarged view of FIG. 7; and,

FIG. 10 is an enlarged side view showing portion '10' in FIG. 4.

The broken line boxes and lead lines in FIGS. 4 and 10 indicate the extents of the detail views and form no part of the claimed design. All other broken lines shown in the drawings illustrate portions of the portable dual-screen monitor and form no part thereof.
